UNITED STATES PATENT OFFICE.

JOSZEF BISCHOF AND AUGUST HEHN, OF DAVIS, WEST VIRGINIA.

PENHOLDER.

1,081,944.

Specification of Letters Patent. Patented Dec. 23, 1913.

Application filed January 17, 1912. Serial No. 671,559.

To all whom it may concern:

Be it known that we, JOSZEF BISCHOF and AUGUST HEHN, both citizens of the United States of America, and both residing at Davis, in the county of Tucker and State of West Virginia, have invented certain new and useful Improvements in Penholders, of which the following is a specification.

The present invention relates to pen holders and has for its object to provide a construction, whereby by a simple manipulation, a pen can be easily expelled without touching it, to be exchanged for a new one.

In order to make our invention more clear, the same is illustrated in the accompanying drawing, which forms a part of this specification and in which similar reference letters denote corresponding parts.

Figure 1 is a longitudinal section through the pen holder; Fig. 2 illustrates the expeller; Fig. 3 is the socket; and Fig. 4 is an enlarged cross section on line 4—4 of Fig. 1.

Referring to Figs. 1—4, our new pen holder consists of a hollow handle or stock *a*, which is provided with the pen retaining device or socket *b*. Movably arranged in said stock *a* is a rod *c*, to the forward end of which the expeller proper is secured. The latter consists of a curved metal piece *d* having a split sleeve-like extension *d'* secured by compression to the rod and a projection

*d*². The piece *d* slidably engages the socket *b* and the pen *e* is adapted to be retained by friction between the bent edges *b'* of the socket and the said piece *d* and to rest with its rear edge against the projection *d*². The rear end of the rod *c* is adapted normally to project outwardly through the stock *a*.

When it is desired to exchange the pen for another, a pressure is exerted upon the outwardly projecting end of the rod, whereby the latter is pushed forward, causing the projection *d*² to expel the pen *e*.

What we claim and desire to secure by Letters Patent is:

A pen holder, comprising a hollow stock, a socket in said stock having bent lateral edges serving to retain the pen point, a rod movably arranged in said stock and projecting outwardly therefrom, a metal piece having a split sleeve-like extension and secured by compression to said rod, said piece slidably bearing in said socket, and a projection on said piece to serve as a rest for the rear end of the pen point.

In testimony whereof we affix our signatures in presence of two witnesses.

JOSZEF BISCHOF.
AUGUST HEHN.
